INVENTOR.

UNITED STATES PATENT OFFICE

134,957

DESIGN FOR A PIN OR SIMILAR ARTICLE

Leon Kalina, New York, N. Y.

Application April 17, 1942, Serial No. 166,600

Term of patent 3½ years

To all whom it may concern:

Be it known that I, Leon Kalina, a citizen of the United States, residing at 1464 Ocean Avenue, in the county of Kings, city of New York, and State of New York, have invented a new, original, and ornamental Design for a Pin or Similar Article, of which the following is a specification, reference being had to the accompanying drawing, forming part thereof, wherein Figure 1 is a front view of a pin showing my new design, and Figure 2 is a rear view thereof.

The features showing on Figure 1 are flush with the surface and the pin is of conventional thickness.

I claim:

The ornamental design for a pin or similar article, as shown and described.

LEON KALINA.
